UNITED STATES PATENT OFFICE.

JOSEPH EDWIN CLOUGH, OF ROCKLAND, DELAWARE.

COMBINATION TAPE-RULE AND CIRCLE-MARKER.

SPECIFICATION forming part of Letters Patent No. 588,129, dated August 17, 1897.

Application filed April 12, 1897. Serial No. 631,684. (No model.)

To all whom it may concern:

Be it known that I, JOSEPH EDWIN CLOUGH, a citizen of the United States, residing at Rockland, in the county of New Castle and State of Delaware, have invented certain new and useful Improvements in a Combination Tape-Rule and Circle-Marker; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in a combination instrument to be used as an ordinary tape-rule and circle-marker; and my object is to provide a simple, cheap, and durable device and at the same time one that can be quickly and easily adjusted to mark a true and complete circle of any diameter.

A further object of my invention is to provide a tape by means of which a scale of one-half inch to the inch can be very readily obtained without the trouble usually experienced in work of this kind, and is also used in connection with the indicator to mark a circle of any desired diameter without computation.

In the accompanying drawings, Figure 1 is a side elevation of my device in readiness to be used as a circle-inscriber. Fig. 2 is a perspective view showing the spring-band and indicator. Fig. 3 is a perspective view in detail of tape and pencil-holder. Fig. 4 is a detail perspective view of the center or pivot pin, and Fig. 5 is a detail view of the indicator-lifting device.

In the said drawings, 1 indicates the casing or housing for the tape, having protruding flanges or rims 2 for the purpose of holding the spring-band 3 in place and to prevent it from slipping laterally from the casing. This band does not entirely encircle the casing, but has the appearance of being severed near the center of one side, the lower end being bent down from a point 4, forming a straight horizontal plate 5. This plate serves as a bearing for the indicator 6, and has on its under surface a center or pivot pin 7, to be used when marking circles. This pin is fastened

to the plate 5 by means of ears 8 and is held open or closed by means of a leaf-spring 9. The upper end of the band 3 is bent up from a point 10 and forms the horizontal platform 11, having upon its upper surface ears 12, between which is fastened, by means of a bearing-pin 13, the lifting-arm 14. At the outer end of the lifting-arm 14 and at right angles thereto is the upright arm 15, which is provided with a button 16 at its upper end. The outer end of the lifting-arm 14 is bifurcated to receive the upper end of the indicator-rod 17, and is held thereto by means of a pin 18, passing through the head 19 of the rod 17. Fastened to the under side of the platform 11 is a cylinder or tube 20, through which passes the rod 17 and serves as a bearing or guide therefor. The lower end of the tube also serves as a bearing for the upper end of the coil-spring 21. Fastened to the lower end of the rod 17 is the indicator 6, by means of which, together with the spring 21, the tape 22 is held at any point desired. The indicator also serves as a bearing for the lower end of the spring 21. The tape 22 is provided upon one half of its upper surface with a scale of standard measure and upon the other half with a scale of one-half inch to the inch, as shown in Fig. 3. At the outer end of the tape is fastened a thimble or pencil-holder 25.

In operation the indicator 6 is raised by pressing the thumb or finger down upon the button 16, allowing the tape 22, which is spring-actuated, to pass in or be pulled out to the point desired. Then removing the thumb from the button the spring 21 forces the indicator down again and clamps the tape firmly between the indicator and the plate 5. Then by placing the pivot-pin 7 in a vertical position and inserting a pencil in the thimble 23 the device is ready for use. Should the diameter of an object be three inches and it is desired to reduce this scale to one-half inch to the inch, it will be seen that by placing the indicator at "3" on the side of the tape marked one-half inch to the inch the reduced diameter is accurately obtained without inconvenience, or should it be desired to mark a circle four inches in diameter it is only necessary to set the indicator 6 at "4" on the half-inch side of the tape, which is equal to the two-

inch mark, which will give a circle four inches in diameter.

It will be understood that the casing 1 incloses the ordinary spring-wound tape, which 5 tape may be either of fabric or steel, with the markings, as described.

In use the point 7 is used as a center pin, the casing being held in the left hand, while the right grasps the pencil and swings the 10 outer end of the tape around to form a circle or any segment thereof.

When not in use, the pivot-pin 7 is to be folded up against the bottom of the plate 5, and should it be necessary to use the tape 15 without the circle device it can easily be removed by simply pushing the lower end of the spring-band 3 down far enough to allow the casing 1 to pass out.

Having thus described my invention, what 20 I claim, and desire to secure by Letters Patent of the United States, is—

1. A combined tape-rule and circle-marker, comprising a casing to receive the tape 22, the tape having markings as shown, and a 25 pencil-holder 23, upon its outer end, a band 3, adapted to surround said casing, one end thereof forming the bottom plate 5, having a hinged point 7, secured to the bottom thereof; the other end upturned to form the horizontal 30 plate 11, said plate provided with the ears 12, upon the upper side, and the tube 20, upon the lower side; a bifurcated lever 14, pivoted between said ears 12, a rod 17, pivoted between the bifurcated ends of the lever 14, and 35 passing through the tube 20, and having an indicator 6, upon its lower end, and a coil-spring 21, surrounding said rod between said tube and indicator, all substantially as shown and described.

40 2. In a combined tape - rule and circle-marker, the combination with the tape-rule

and case thereof, of a band 3, having upper and lower horizontal ends 5, and 11, the lower end 5, having a folding pivot-point 7, secured to the lower face thereof, the upper face being smooth for the tape 22, to slide upon; the upper end 11, having a suitably-pivoted lever-arm 14, pivoted to the rod 17, by which said rod may be raised and lowered, a tube 20, secured to said end 11, to serve as a guide for 50 the rod 17, a spring 21, surrounding said rod, having its bearing against the indicator 6, at the lower end of said rod, and against the lower end of the tube 20, and adapted to hold said indicator normally against the upper 55 face of the lower end 5, as set forth.

3. In combination in a combined tape-rule and circle-marker, the case 1, having the rims 2, and adapted to contain the tape 22; the spring-actuated tape 22, having the double 60 row of graduations, and carrying the pencil-holder or thimble 23, upon its outer end; the band 3, having the lower plate 5, carrying the point 7, between ears 8, and held by the spring 9, upon its lower face, and the horizontal upper plate 11, provided with the ears 12, on its upper face, and the tube or rod-guide 20, upon its lower face; a bifurcated lever 14, pivotally mounted between the ears 12, and having the upturned end 15, provided with a button 16, and the rod 17, pivotally secured to the lever 14, at its upper end, passing through the tube 20, carrying the spring 21, and provided with the indicator 6, at its lower end, all substantially as shown and described. 70

In testimony whereof I affix my signature in presence of two witnesses.

JOSEPH EDWIN CLOUGH.
